SHOETREE

Arthur R. Anderson, North Arlington, N. J.

Application May 28, 1938, Serial No. 210,726

11 Claims. (Cl. 12—128.6)

My invention relates to shoe trees and more particularly to shoe trees which may be quickly adapted to fit properly after being inserted within the shoes.

Very few shoe trees are now in use which can be adjusted to proper length while they are within the shoes. Many of these trees are adjusted by means of screw devices which are not only expensive but are slow and laborious to operate. A few shoe trees have resilient sections which tend to spring the trees into position when released after insertion in the shoes but a major difficulty with these resilient trees lies in the selection of a suitable resilient or spring section. When the spring section is light, so as to be easily bent, it is often too weak to properly fit the shoe tree into the shoe. Where the spring is very strong it cannot easily be bent, especially by people with weak hands, and is therefore objectionable.

Practically all other types of shoe trees have to be adjusted to proper length before being inserted within the shoes and then are usually expanded to fit the shoes in some suitable manner such as by straightening out a broken toggle joint. These trees are ordinarily objectionable because of the time usually required to make trial adjustments before a suitable adjustment is found since the shoe tree must be removed from the shoe for each adjustment. Furthermore, these adjustments are usually step by step arrangements and do not continuously increase the length of the tree so that proper fitting of the shoe tree to the shoe is hardly ever obtained.

With the above defects of the prior art in mind it is a major object of the present invention to provide a novel shoe tree which is inexpensive to manufacture, sturdy and simple in construction and positive and powerful in action so that it can be quickly and easily adjusted to proper length without buckling within a shoe in which it has been inserted and just as easily removed from the shoe when desired.

A further object of my invention is to provide a novel shoe tree having slidably connected heel and toe sections which can be inserted within a shoe in a contracted state and then quickly and easily expanded to properly fit the shoe. Specifically the heel and toe sections are also pivotally interconnected to permit easy insertion of the tree within the shoe.

It is still a further object of my invention to provide a shoe tree having novel contraction and expansion control means wherein one continuous pushing movement of the control handle will

force the shoe tree into intimate contact with the shoe and at the same time expand the same to fit the shoe properly and wherein a continuous pulling movement of the control handle serves to contract the shoe tree and subsequently remove it bodily from the shoe.

A further object of the invention is to provide a shoe tree having slidably connected heel and toe sections and wherein novel cam operated link means are designed to speedily effect and positively maintain longitudinal separation between the heel and toe sections within a shoe. In specific embodiment of the invention suitable means are provided for limiting separation between the section and preventing said section from becoming entirely disconnected from each other.

A further object of my invention is to provide a novel shoe tree made up of relatively slidable heel and toe sections wherein the heel and toe sections may be quickly and easily relatively displaced longitudinally within a shoe until the shoe tree is of proper length to fit properly within the shoe.

Further objects of the invention will presently appear as the description proceeds in connection with the annexed drawing and the appended claims.

Figure 1 is a top plan view of a shoe tree illustrating an embodiment of the invention. In Figure 1 the shoe tree is in a contracted state.

Figure 2 is a side elevation of the shoe tree of Figure 1 illustrating the cam operated linkage for relatively displacing the heel and toe sections.

Figure 3 is a side elevation in section taken along line 3—3 in Figure 1 but in which the parts of the shoe tree are shown in partially expanded condition.

The shoe tree illustrated in the drawing is made of two separate, preferably integral parts comprising a heel section 11 and a toe section 12. These sections are preferably made of hard wood or some other suitable rigid material and all of the surface portions thereof which are liable to contact the shoe within which the tree is fitted are preferably rounded and smoothed. A good grade of wood has been found to be highly suitable. The toe section is provided preferably with a plurality of longitudinal slots 13 which not only reduce the weight of the toe section but permit adequate ventilation of the interior of the shoe.

Adjacent end surfaces 14 and 15 of sections 11 and 12 respectively, are preferably flat and are

adapted to abut when the shoe tree is in its contracted state, or position of shortest length as shown in Figure 2. Surfaces 14 and 15 preferably are inclined forwardly toward the toe section 5 to allow free pivotal movement of the toe section at all times as will later be explained.

The top surfaces of the heel and toe sections are cut away at 16 and 17 respectively, to provide relatively flat areas at their adjacent opposing ends which are aligned cooperatively when the shoe tree is fully contracted as shown in Figures 1 and 2. An upstanding shoulder 18 extends from the cut away portion 16 to the rear end of heel section 11 and is provided with a 10 substantially centrally disposed cylindrical socket 19 which extends a substantial distance toward the bottom of heel section 11.

Heel section 11 and toe section 12 are provided with substantially centrally located, aligned, narrow longitudinal slots 21 and 22 respectively, which are open at adjacent ends at surfaces 14 and 15 respectively. A relatively wide groove 23 is formed in heel portion 11 and extends from bore 19 to the rear end of slot 22. As shown in 25 Figure 2, groove 23 is provided with a forwardly and upwardly inclined bottom surface 24 which terminates at portion 16 adjacent surface 14. Slots 21 and 22 are preferably of slightly less depth than bore 19, and slot 22 extends forwardly 30 from surface 15 to a point near the front edge of cut away portion 17.

The heel and toe sections are interconnected by a rigid, flat link 25 of metal, or some other suitable material, disposed with its opposite end 35 portions in slots 21 and 22. Link 25 is pivoted adjacent its front end upon a removable pivot pin 26 which is preferably non-rotatably secured in a suitable aperture 30 in toe section 11 and extends through the upper part of slot 22 approximately 40 normal thereto. The thickness of link 25 is slightly less than the width of slots 21 and 22 and the width of link 25 is materially less than the depth of slots 21 and 22. Front toe section 11 is therefore, freely pivotally connected to the 45 front end of link 25.

Heel section 11 is slidably connected to the rear portion of link 25. A pair of removable guide pins 27 and 28 are non-rotatably mounted in suitable apertures 29 and 31 in heel section 50 11 and extend through slot 21 and groove 23 respectively, substantially normal to link 25. Guide pins 27 and 28 and pivot pin 26 are preferably in substantial horizontal alignment when the tree sections are in the position of Figure 1. Link 25 is provided with a pair of longitudinally 55 extending slots 32 and 33 through which pins 27 and 28 respectively extend so that heel section 11 is longitudinally slideable with respect to link 25.

Link 25 is provided adjacent its rear end with 60 a rigid arm 34 which extends upwardly and forwardly therefrom, through and above groove 23. Arm 34 is preferably integral with link 25 although it may be a separate element rigidly secured thereto. Arm 34 is provided at its upper 65 end with an enlarged stop formation 35 for a purpose later to be described.

A plunger 36, of wood or any other suitable material, is slideable vertically in bore 19 and is provided with an enlarged handle portion 37 for 70 convenient manipulation. Below handle 37, plunger 36 is provided with a collar 38 from which a bar 39 extends forwardly and substantially horizontally. Adjacent its forward end, bar 39 is formed with a lateral flange 41 which is slotted 75 at 42 to slidably receive arm 34. Slot 42 is only

slightly larger than the cross section of arm 34 and slot 42 is designed to serve as a cam slot while arm 34 functions as a cam follower. Bar 39 may be secured to plunger 36 in any suitable manner and may even be integral with the 5 plunger if the latter is composed of metal or some other similar rigid material.

When plunger 36 is vertically reciprocated in bore 19, such vertical motion will be translated into relative horizontal movement between link 10 25 and heel section 11 due to the camming action of slot 42 and arm 34. Groove 23 is of such width as to allow vertical passage of flange 41 as plunger 36 nears the bottom of its stroke. Plunger 36 is prevented from being pulled entirely out of 15 bore 19 by stop formation 35 which cooperates with the top of flange 41 when the plunger has reached its upper limit.

When the shoe tree is in contracted position as shown in Figure 2, surfaces 14 and 15 are preferably in abutment, guide pins 27 and 28 are disposed adjacent the forward edges of their respective cooperating slots in link 25 and the upper surface of flange 41 is substantially in contact with stop formation 35. The permissible expanded length of the shoe tree may be determined by the engagement of the lower end of plunger 36 and the bottom of bore 19, or by the engagement of guide pins 27 and 28 with the rear edges of their respective cooperating slots in link 25. 30

The heel and toe sections cannot be entirely detached from one another due to their above described method of connection to link 25, and stop formation 35 prevents removal of plunger 36. Preferably collar 38 is integral with bar 39 35 and may be bent about plunger 36 after bar 39 has been slidably connected to arm 34 by rocking slot 42 over stop formation 35. However, the preferred manner of assembling the device is to arrange the parts in operative relation and then drive pins 26, 27 and 28 into their respective apertures. 40

Operation

The shoe trees of the invention are made in different sizes suitable for properly fitting different sizes of shoes. After selecting a shoe tree of desired size, it is collapsed to a contracted state preferably by grasping heel section 11 in one hand and pulling outwardly on handle 37 with the other hand. This causes link 25 to slide 45 rearwardly along guide pins 27 and 28 and toe section 12 is pulled rearwardly into abutment and alignment with the heel section. 50

The shoe tree is then placed in the shoe by inserting the toe section and pushing the tree forwardly as far as possible. Usually the tree is broken to effect this operation by rocking the heel section in a clockwise direction about its pivot at 26. As shown in Figure 2, link 25 terminates adjacent pivot 26 and surfaces 14 and 15 are forwardly inclined. This arrangement permits such free pivotal movement of heel section 11 in a clockwise direction about pivot 26. After forward motion of the toe section has stopped, the heel section is pushed inwardly to 60 rock it in a counterclockwise direction about pivot 26 and seat it snugly within the rear portion of the shoe. Usually this movement of the heel section is effected by grasping handle 37 and pushing inwardly until the heel section is properly seated. At this time the shoe tree will be disposed within the shoe in the contracted state shown in Figure 2. To expand the tree to properly fit the shoe it is necessary only to continue to push downwardly on handle 37 to depress 65 70 75 80 85 90 95 98 99 100

plunger 36 and thereby cause link 25 to be longitudinally displaced with respect to its guide due to the cam action at arm 34 and slot 42. The shoe tree is shown in partially expanded condition in Figure 3. The bottom of plunger 36 may cooperate with the bottom of bore 19 to limit permissible expansion of the tree or if desired, the same result may be obtained by engagement of guide pins 27 and 28 against the rear edges of their respective guide slots.

Often the length of the shoe to be fitted is such that proper fitting is attained before plunger 36 has reached the bottom of bore 19. However, cam arm 34 and cam slot 42 are so designed that they will maintain the shoe tree in such maximum obtainable expanded position at any point between the fully contracted state shown in Figure 2 and a fully expanded state. Thus, it is necessary only to push handle 37 downwardly until the above mentioned stops prevent further separation of the heel and toe sections, or until the shoe itself resists further expansion. In either case the angularly disposed edges of cam slot 42 and cam arm 34 will cooperate to frictionally lock the tree sections in expanded position.

In order to remove the shoe tree from a shoe, it is necessary only to grasp the shoe with one hand and pull upwardly on handle 37 with the other. Initial movement of handle 37 will release the frictional lock at the cam portions and cause the tree sections to be displaced toward each other, with the parts moving in opposite directions to those above recited in describing expansion of the shoe. After the shoe tree has contracted sufficiently, continued pulling on handle 37 will rotate heel section 11 in a clockwise direction about pivot 28 and enable the whole tree to be subsequently pulled bodily out of the shoe with a single continuous motion.

Although the embodiment of the invention illustrated in the drawing discloses a shoe tree in which some of the adjustment parts project from the tree sections, it will be apparent that the same adjustment could be fully housed within a shoe tree of suitable size except for projecting handle 37 and the upper part of plunger 36. Such a completely housed mechanism would present a pleasing appearance to the eye and would have no projecting points or corners which might become entangled with clothing or other objects.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A shoe tree comprising cooperating heel and toe sections slidably connected together, means for relatively separating said sections to fit a shoe in which they have been inserted, a manual control handle for said means slidably generally toward said shoe to cause separation of said sections and slidably generally away from said shoe to cause said sections to move toward each other whereby said handle is manually grasped and pushed to force said tree into firm contact with said shoe and expand the tree with one continuous motion and said handle may be grasped and

pulled to effect contraction of said tree and subsequent removal of said tree from said shoe with another continuous motion.

2. A shoe tree comprising cooperating heel and toe sections, means slidably connecting said sections for relative longitudinal movement, means operable while said tree is in a shoe for causing relative longitudinal displacement of said sections to lengthen said tree to fit said shoe and automatic frictional locking means for positively maintaining said shoe tree in said lengthened state.

3. A shoe tree comprising cooperating heel and toe sections, means for slidably and pivotally interconnecting said sections and means for adjusting said shoe tree to fit a shoe into which it has been inserted comprising interfitting cam slot and slide means for relatively longitudinally displacing said sections, said cam means also providing a positive frictional lock for maintaining said shoe tree in lengthened state.

4. A shoe tree comprising cooperating heel and toe sections, interconnecting means pivotally attached to one section and slidably engaged with the other of said sections and means slidably mounted on said other section and movable substantially normal to said interconnecting means and cooperating with said interconnecting means to cause relative longitudinal displacement of said sections.

5. A shoe tree comprising cooperating heel and toe sections, means pivotally attached to said toe section and slidably engaged with said heel section and cam means slidably mounted on said heel section cooperating with said first-named means for relatively longitudinally separating said sections upon sliding movement of said slidable cam means.

6. A shoe tree comprising cooperating heel and toe sections, a link pivotally connected adjacent one end to said toe section, guide means on said heel section for slidably receiving the other end of said link, means projecting upwardly from said link adjacent said heel section and slidable means on said heel section for engaging said projecting means to displace said link along said guide means.

7. In a multi-section shoe tree, adjusting mechanism comprising a link slidably mounted in one section of said tree, an angularly extending arm rigid with said link and extending upwardly therefrom, control means slidably mounted on said section and cooperating cam surfaces on said arm and said control means.

8. A shoe tree comprising cooperating heel and toe sections which are provided with aligned longitudinal slot formations, a link disposed within said slots, said link being pivotally connected to said toe section and slidably disposed within the slot in said heel section, means for limiting the travel of said link along said heel slot, an arm rigid with said link extending upwardly from said link at the heel section and a control element substantially vertically slidably disposed on said heel section and provided with a forwardly extending cam member, said cam member being apertured to slidably receive said arm so that when said control element is adjusted vertically said cam member causes said link to be displaced longitudinally along said heel section.

9. The shoe tree of claim 8, wherein said control element is provided with a handle which is accessible for manipulation when said tree has been inserted in a shoe.

10. A shoe tree comprising cooperating heel

and toe sections, a link pivotally connected to one section and slidably connected to the other section, a cam arm integral with said link projecting upwardly from said link, a slideable control member on one of said sections and means on said member cooperating with said cam arm for translating sliding motion of said member into relative longitudinal displacement of said sections.

11. In a shoe tree, a link for pivotally interconnecting heel and toe sections having an upwardly projecting arm and a control arm slidably mounted upon one of said sections, one of said arms being provided with a slotted guide within which a portion of the other arm is slidably received.

ARTHUR R. ANDERSON.
